UNITED STATES PATENT OFFICE.

VICTOR O. MILLS, OF CHICAGO, ILLINOIS.

HOOK AND EYE.

SPECIFICATION forming part of Letters Patent No. 655,884, dated August 14, 1900.

Application filed February 21, 1900. Serial No. 6,039. (No model.)

To all whom it may concern:

Be it known that I, VICTOR O. MILLS, a resident of Chicago, in the county of Cook and State of Illinois, have invented a certain new and useful Hook and Eye, of which the following is a specification:

My invention relates to hooks and eyes generally; and my object is to provide a novel and efficient construction thereof whereby the same may be readily attached or detached from the cloth and sewing thereof dispensed with.

In the accompanying drawings, Figure 1 is an elevation of my hook and eye together, both being enlarged considerably above the average size of such articles; Fig. 2, a side elevation thereof; Fig. 3, a section on line 3 of Fig. 1; Fig. 4, an elevation of the hook and eye secured to cloth; Fig. 5, an elevation of a modified form of hook; Fig. 6, a side elevation thereof, and Fig. 7 a section on line 7 of Fig. 5.

Both the hook and eye are preferably formed of a single piece or strip, usually a single continuous wire, which may be of any suitable diameter and length, according to the size of hook and eye desired or to the particular uses to which they are to be applied. While the forms shown are being described, it is therefore to be borne in mind that the proportions and the exact lines may be changed or varied without departing from the spirit of my invention.

In general terms the hook and eye consists of a hook and eye proper and an attachment member, which may be conveniently termed a "shank."

In the hook and eye shown in Figs. 1 to 3 the hook is made of a continuous wire bent at its middle so as form the hook proper, (marked 2,) which preferably has the two lateral swells 3. Each wire is bent downwardly at 4 and then outwardly, making short members 5. Each wire is then given an outwardly extending or lateral loop 6, from which the portion 7 extends to a suitable distance and preferably substantially in a line with the members 5. The last wires 8 of the wire are then bent laterally—that is, in such manner that, as clearly shown in Fig. 2, they will lie in the same plane as the portions 7, practi-

cally forming a U. The extreme ends 9 of the wire may be pointed and are adapted to enter the loops 6 and rest therein in their normal condition. These loops 6 preferably have a restricted opening on their inner adjacent sides into which the pin-point ends of the wire snap, whereby the accidental displacement or release of such ends is prevented. As illustrated in Fig. 3, the loops 6 are open on their inner adjacent sides and may be provided with a drop or socket 10 to receive the ends of the members 8, although obviously such socket is not essential, but may be entirely dispensed with. However, it may be found advantageous in case there should be any liability of the eye engaging underneath the points 9 in unhooking. The eye embodies the same general principles of means for attachment to the cloth and may also be made from a continuous wire, as shown. The wire is first looped at the center to make a loop 11 or eye proper, and the remainder of the wire is bent to form the lateral loops 12, outwardly-extending portions 13 and the extreme portions 14 extending inwardly—that is, toward the hook—and entering the loops 12. So far as the means of fastening to the goods is concerned the eye is similar to the hook. The eye is of course fastened to the cloth in the same manner as the hook, and consequently the described operation of one applies to both. In attaching the hook the members 8 are removed from the loops 6 by forcing them inward, so that they will then be below and outside the loops. The points 9 are then inserted through the goods at the proper place, and the entire hook is drawn substantially parallel with the goods, the members 7 pressing closely on top the goods and the members 8 closely beneath, owing to the fact that such latter members are not bent downwardly at right angles to the goods, but laterally and in the same plane. When the hook has thus been drawn sufficiently to engage enough of the cloth, either the hook or the cloth may be given a sharp movement to cause the points to pass through in the opposite direction. The members 8 are then inserted in their loops by springing them inward and then allowing them to assume their normal position in such loops.

The swells 3 on the hook permit positive insertion or removal of the eye, but prevent accidental disengagement.

Both the hook and eye have a broad bearing, owing to the laterally-extending loops and the width of the portions directly engaging the cloth, so that a firm fastening or attachment covering a sufficient surface of the cloth is obtained. Furthermore, when the portions 8 are in substantially the same plane as the portions or members 7 all such portions are caused to lie flat and close to the cloth, which is practically engaged between or interwoven with such portions of the hook or eye.

While the members of the shank are described and illustrated as lying in the same plane and while such arrangement may be preferable or desirable in certain cases or with certain sizes of hook or certain thicknesses of cloth, yet it will be understood that my invention is not limited to such arrangement except as to those claims expressly specifying that feature.

The modification of hook shown in Figs. 5, 6, and 7 embodies the same general features as in the other hook, but is provided with means for preventing disengagement of the eye. The hook proper (marked 15) is formed at the middle of the wire, which is bent downwardly and outwardly. Lateral loops 16 and 17 are also formed; but instead of the wires then continuing outwardly the wires cross below the hook. The wire of loop 16 continues at right angles to form the portion or member 18 and the member 19, bent laterally and extending back in substantially the same plane as portion 18 and finally entering loop 17. The wire of loop 17 extends outwardly—that is, toward the right—(see Fig. 5,) and then is curved upwardly above the crossing of the loop-wires and preferably as high or higher, if desired, than the plane of hook 15, as shown in Fig. 6. A hump 20 is thereby formed. The wire then forms the portions 21 and 22, similar to 18 and 19, the end 22 entering loop 16. This hook is attached to the cloth in the same manner as the form first described, and any suitable eye may be used. When the eye is inserted in the hook, it springs the hump downward and is afterward held in the hook against accidental disengagement.

It is obvious that whether in the process of forming the hook the hook proper is formed first or not is immaterial, inasmuch as the process may begin at the free ends or pin-points and end with the formation of the hook or the eye. Therefore it is to be understood that the invention relates to the finished hook or eye and the claims are directed thereto regardless of the formation or bending of the members in point of time.

I claim—

1. As a new article of manufacture, a hook or eye having a hook or eye proper and an attachment member or shank with pin-point

ends for attachment to the cloth, said shank having loops which have an opening at their inner adjacent sides and which have a socket 70 on their bottom portion, said ends being insertible in the loops only through such openings and adapted to rest in such sockets.

2. As a new article of manufacture, a hook or eye having a hook or eye proper and a shank with a pin-point end for attachment to the cloth, the members of the shank lying in substantially the same plane, loops on such shank substantially at right angles to the plane of the shank, such loops having a restricted opening on their inner adjacent sides into which such pin-point ends snap.

3. As a new article of manufacture, a hook or eye comprising a strip or wire looped at the middle to form the hook or the eye proper, each 85 of the ends remaining being bent to form, first, a loop in a plane substantially at right angles to the plane of the hook and eye, second, an outwardly-extending member and, third, an inwardly-extending portion bent 90 laterally of, and in the same plane as, said member, the extreme free ends of said portions entering said loops.

4. As a new article of manufacture, a hook or eye comprising a strip or wire forming a 95 hook or eye at its middle, the ends being formed into partial loops and finally into a U which is attached to the cloth, such loops rising above the plane of said U and in a plane substantially at right angles to the plane of 100 the hook or eye.

5. As a new article of manufacture, a hook or eye comprising a strip or wire forming a hook or an eye at its middle, the remaining ends being first formed in partial loops in a 105 plane substantially at right angles to the plane of the hook or eye with an entrance on their inner adjacent sides, and then formed substantially into a U, the extreme ends being adapted to be sprung inward to enter said 110 loops and then to resume their normal relative position but in the loops said loops rising above the plane of the U.

6. As a new article of manufacture, a hook having a hook proper and an attachment 115 member or shank with a pin-point end for attachment to the cloth, such shank lying in a plane parallel to the plane of the hook and having a loop in a plane substantially at right angles to the plane of the hook and extending 120 toward such hook, said pin-point end of the shank resting in such loop.

7. A garment-hook having a hook proper, portions 5, lateral loops 6, with sockets 10, and members 7 and 8 which form a U, the ends 125 of members 8 entering said loops and resting in said sockets.

8. A garment-hook having a hook proper, loops 6 below the hook proper and in close proximity thereto and members 7 and 8 extending from the loops and in the form of a U, the ends of members 8 entering said loops the tops of the loops being above the plane of members 7 and 8.

9. A hook comprising a hook proper having swells 3, bend 4, short portions 5, loops 6 below the hook and open on their inner adjacent sides, said loops extending laterally 5 and upwardly in proximity to the hook and substantially in a plane rearward of the swells, and members 7 and 8 extending from said loops and forming a **U**, the extreme free ends of members entering said loops.
10. As a new article of manufacture, a hook comprising a strip or wire bent to form a hook proper, a loop under such hook proper and finally bent to form a **U**, such loop alone extending into close proximity to the hook proper to prevent accidental disengagement 15 of the eye from the hook.

11. As a new article of manufacture, a hook comprising a strip or wire bent at its middle to form a hook proper, the remaining ends being bent to form loops under the hook proper and finally formed into two **U**'s, such loops engaging the free ends of the wire and alone extending into close proximity to the hook to prevent accidental disengagement of the eye from the hook such eye having free 25 entrance under the hook until the loops are reached.
